UNITED STATES PATENT OFFICE.

ROBERT W. MACDONALD, OF CHICAGO, ILLINOIS, ASSIGNOR TO WUNDUR CABINET LEDGER COMPANY, OF CHICAGO, ILLINOIS, A CORPORATION OF ILLINOIS.

LEDGER CABINET.

Application filed January 10, 1921. Serial No. 436,169.

To all whom it may concern:

Be it known that I, ROBERT W. MACDONALD, a citizen of the United States, residing at Chicago, in the county of Cook and 5 State of Illinois, have invented certain new and useful Improvements in Ledger Cabinets, of which the following is a specification.

This invention relates to a ledger cabinet 10 such as is adapted to receive leaves or cards on which is contained any desired data; more particularly in connection therewith, it is concerned with certain improvements in an adjustable block adapted to support the 15 cards or leaves within the cabinet. The invention is concerned also with other objects all of which will appear from the detailed description to follow, wherein reference is made to the accompanying drawing which 20 shows an exemplification of this invention in the manner following:

Figure 1 is a side elevation of the cabinet with one side wall removed;

Fig. 2 is a transverse section therethrough 25 taken on line 2—2 of Fig. 1;

Fig. 3 is a plan view thereof, with the side wall replaced;

Fig. 4 which illustrates a modified construction is a longitudinal section taken 30 on line 4—4 of Fig. 5; and

Fig. 5 is a transverse section taken on line 5—5 of Fig. 4.

The cabinet or box A shown in Figs. 1—3 may be constructed with a base 10 from 35 which upstands ends 11 and 12 between which is a fixed side 13 and a removable side 14. It is preferred that the corners of the box be reinforced as by means of angle plates 15, those which are situated adjacent 40 the removable side 14 being secured to the ends only so as to provide outer stops therefor. Within the cabinet so formed may be received a stack B of cards or leaves 16. Internally of the box at each end may be arranged a block 17 extending from side to side and provided with a base of substantial width, the inner face of each block being slanted downwardly, as shown in Fig. 1. The effect of these two blocks so arranged is 45 to provide abutments for the stack of leaves 50

or cards, so that they may incline either way, as desired, and also to provide inner stops for the removable side 14.

I have provided within the cabinet an adjustable block C, usually termed the "follower", which comprises a base plate 20 which is connected at its forward edge with a supporting plate 21 that extends upwardly and rearwardly to support the card stack, a brace block 22 being employed to maintain 55 the two plates in rigid relation. The base extends transversely from the fixed wall 13 to a rib 23 that is mounted along the bottom 10 adjacent the removable side 14, permitting the follower to be moved lengthwise of 60 the cabinet between this rib and the wall 13 which afford guides therefor. Arranged upon the side wall 13 just above the base 20 is a second rib 24 that acts to prevent tilting movement of the follower in the direction of 65 the side 14 of the cabinet. The supporting plate 21 is suitably cut away adjacent this rib for purposes of clearance, as clearly appears in Fig. 2. By slightly tilting the follower block toward the side 13, the opposite 70 side of the base is lifted sufficiently to clear the rib 23 following which the block C may be shifted sidewise and be removed from the cabinet. It is to be understood, of course, that the block may be removed in this manner only when the side 14 is not in place. 75

The leaves or cards 16 which are adapted to be used with a cabinet so constructed may be of the usual kind with their lower corners beveled as at 25, so as to clear the ribs 80 23 and 24. In addition, a lock rod 26 may be employed, if desired, being entered through suitable openings in the end blocks 17, and passing through an opening 27 in each leaf, as well as through the follower block. 85 Where such a rod is used, its withdrawal will, of course, have to take place before the follower block can be removed. 90

Each of the leaves may also be notched at one or more places adjacent its bottom edge, 95 as shown at 30 and 31 in Fig. 2. These notches have no function when the side 14 is in place, but when it is down or entirely removed from the cabinet, and the lock rod 26 is pulled out, any selected leaves or cards 100

may be offset from the remainder of the stack by a distance sufficient to present either of the notches 30 or 31 over the rib 23 which serves as a means of defining the extent of 5 offset. When so positioned, the lock rod may be replaced to lock the leaf stack within the cabinet, it being understood that appropriate additional openings 32, 33, etc., should be formed in each leaf to permit of the rod 10 passing therethrough when offset to the distance predetermined by the notches.

The entire cabinet that I have shown and described herein may be formed of wood, and accordingly may be constructed at small 15 expense. With the exception of the lock rod, the corner plates, and fastening devices, the parts may be made with wood working machinery, and the resulting structure will not only be light and strong, but will be very 20 serviceable in providing for a cabinet an adjustable follower block which may be moved lengthwise to any desired position to support the cards or leaves that are placed therein. Owing to the feature of having the base 25 plate 20 in underlying relation to the rib 24, the follower block is prevented from tilting forwardly or backwardly and consequently derives therefrom all the necessary reinforcement for the work which it is called 30 upon to perform.

In Figs. 4 and 5 is represented a similar construction of follower block used in a cabinet wherein the ends and sides are fixedly secured to the base. Accordingly I 35 have applied to the several parts of this cabinet reference numerals which correspond with those used in the remaining figures. It will be noted, however, that the bottom of the cabinet is without any rib, 40 as both side walls thereof co-operate with the base of the follower block to guide its longitudinal movements. In this cabinet, however, I have shown the rib 26 which is secured to the wall 13 as terminating at 30, 45 so as to leave a gap between this end and the cabinet end 12 of sufficient width to allow the follower block to be lifted vertically from the cabinet whenever it is shifted to end position therewithin. The dotted 50 lines in Fig. 4 indicate the block when moved near the end wall 12 in position for removal from the cabinet. While the follower in this position is no longer subject to the action of the rib 26 which prevents 55 its tilting forwardly or backwardly, the block is so close to the end wall 12 as to derive support therefrom sufficient for all purposes.

The invention which I have herein shown 60 and described is one which is very simple in construction and use. It embodies the novel features of an adjustable follower block which receives support in a very novel manner and which may be removed from

the cabinet with a minimum of effort. It is 65 obvious, of course, that the invention may be embodied in forms other than the ones herein shown, so that in respect of any changes or modifications embodying the novel features hereinafter claimed, I desire 70 that the same be included within the scope of this patent.

I claim:

1. In a cabinet having a bottom, ends, and a single side secured together, an inwardly projecting rib arranged upon the side in spaced relation to the bottom, a follower having a base plate adapted to extend beneath the rib, the follower being provided with upstanding means for supporting a 80 stack of leaves, and other means for normally preventing lateral shifting of the follower whereby its base is retained beneath the rib to prevent tilting movement of the follower within the cabinet, substantially as 85 described.

2. In a cabinet having end walls, a single side therebetween, and a bottom to which these parts are connected, means projecting inwardly from the side wall near the bottom 90 but spaced therefrom, a follower within the cabinet adapted to be moved longitudinally thereof, a device on the follower engaged by said means for preventing tilting of the follower longitudinally within the cabinet, 95 a second means upon the cabinet bottom adapted to co-operate with the follower to normally prevent lateral shifting thereof, whereby the follower remains engaged by the first means, said means on the cabinet 100 bottom permitting the follower to tilt laterally and out of engagement with both of said means whereby the follower may be freely removed from the cabinet, substantially as described.

3. In a cabinet having a bottom, two ends, and a single side fixedly related thereto, a follower adapted for longitudinal movement within the cabinet, guiding means adapted to retain the follower within the 110 cabinet, leaves adapted to be stacked edge-wise within the cabinet against the single side thereof, each leaf having a notch in its bottom edge arranged to co-operate with the guiding means to determine a definite 115 distance of offset with respect to the remainder of the leaf stack, and a second side removably positioned between the cabinet 120 ends adapted to confine the leaves therein against lateral shifting, substantially as described.

4. In a cabinet having a bottom, a single side, and ends secured thereto, a follower adapted to be moved longitudinally within the cabinet and provided with a base extending adjacent the cabinet side, means for guiding the follower in its movements within the cabinet, whereby its base remains ad-

5 jacent said side wall, means extending inwardly from the cabinet and in engagement with the base adapted to prevent forward or rearward tilting movement of the following, and leaves adapted to be stacked within the cabinet with their side edges closely adjacent the cabinet side, the leaves

and inwardly extending means being formed each to clear the other, substantially as described.

ROBERT W. MACDONALD.
